UNITED STATES PATENT OFFICE.

MARIO FRANCO, OF TURIN, ITALY.

SEAMLESS HEAD AND PART OF TOY OF FELT OR THE LIKE.

1,407,649.

Specification of Letters Patent. Patented Feb. 21, 1922.

Application filed January 29, 1921. Serial No. 441,061.

To all whom it may concern:

Be it known that I, MARIO FRANCO, a citizen of the Kingdom of Italy, residing at Turin, 18 Via Amedeo Peyron, have invented certain new and useful Improvements in Seamless Heads and Parts of Toys of Felt or the like; and I do hereby declare the following to be a full, clear, and exact description of the invention, such as will enable others skilled in the art to which it appertains to make and use the same.

This invention relates to the manufacture of toys of felt or similar soft materials.

It has been noted that the recent manufacture of toys, such as dolls and animals, has particularly produced that kind of toys unbreakable of felt or like soft materials, full of oakum or padding or other light and soft stuff.

Those toys however are often not very nice, because many stitches or seams are necessary to join the several pieces, these stitches corresponding always to the most important parts of the head, so that they generally disfigure the face in the middle, which is objectionable, from an aesthetic standpoint. Besides the working of sewing the several cut and stamped pieces is long and difficult, and also expensive.

My invention has for its object to provide means for the manufacture of heads and other parts of dolls or animals, of felt, leather, stuff, or similar soft materials in one piece, without stitches or seams, taking advantage of the yielding of the said coats, and stamping them by means of suitable moulds. The figures of the annexed drawings show diagrammatically the parts embodying my invention, used by way of example to perform a doll's head.

With similar moulds suitably modified I can obtain heads of several animals, and other parts of the human and animal bodies.

Fig. 1 is a perspective view of a mould or pattern, composed of many pieces, i. e. a sectional mould or pattern, of a doll's head.

Fig. 2 is an elevation of one of the box- or closed- moulds, of which two are used, corresponding to the mould Fig. 1.

Fig. 3 shows the way to begin the spreading and the stamping of the coat of the soft material, as it will be hereinafter explained.

The pattern Fig. 1 will be produced in as

many pieces as the amount of the cavities in the mould will require, and may be indifferently made up of wood, or metal, or other suitable material; the box- or closed-mould Fig. 2 is generally made up of metal, in order to allow it to be strongly pressed and caused to adhere to the pattern.

It has been proved however that the box-mould Fig. 2, can be made of hard rubber, because this latter fits with its projections in all the cavities of the pattern, whilst maintaining a certain elasticity in order to support the residual tension of the felt or similar material, allowing it to be slightly deformed, during the moulding operation.

In the drawing the pattern consists of parts A B C D E F, divided each other through vertical planes, reciprocally parallel or at a right angle. The box-or-closed-mould is usually made in two parts, one of which is shown in Fig. 2.

The mode of operation is the following:

I prepare the felt, or leather, coat or covering by tarring same with a light daubing of glue. When the coat is dry, I expose it to the evaporation of the boiling water, and during the softening action of this latter, I stretch the felt or equivalent upon the pattern accurately adjusting and strongly pulling it by all sides. After having adapted the felt or the like to the pattern, by evaporating it again, if necessary, on the boiler, I bind or nail with pins its lower edge G H (Fig. 3) to the bottom of the said pattern. Then I again expose the pattern so covered to the efficient action of the steam of the boiler, in order to make the material as soft as possible, and I shut it in proper position within two closed moulds such as the one shown in Fig. 2, conveniently warmed, and I press the outward moulds so that the corresponding parts of the pattern and of these latter exactly register, sufficiently compressing the felt, or equivalent. In few moments of compression, the material moistened by the steam, will be dry and hardened, and the pattern can be removed from the moulded part.

Referring more particularly to the Fig. 3 and to the last described operation, I prefer to employ, instead of a flat piece of felt, leather, or equivalent, a small bag or hood of the same material, of suitable sizes to fit almost exactly to the mould. This bag, whilst being in a single piece, may also have some stitches, at a right angle with the edge

corresponding to G H of Fig. 3, in order to facilitate its fitness to the contractions of the mould, where it can be useful to reduce the number of the material's folds.

5 In place of using a mould, I can do by hand the complete moulding and finishing operation, by means of sculptor sticks or similar tools. It will be easily understood that the same system hereinbefore described 10 and illustrated in the annexed drawings as applied to a doll's head may be employed to form any part whatever of toys, of the kind referred to.

Furthermore I can embody my invention 15 also by employing a mould, such as that of Fig. 1, but in a single piece of material, such as gilder's plaster or macerated paper, to be broken and removed after the moulding operation.

20 I can do that as much as the aforesaid stitches, without departing from the principle of the present invention, which is to

provide toys so that they don't have stitches or seams in the most visible parts.

What I claim is:

25 In the manufacture of toys, such as dolls and animals, the method of moulding different toy parts from a single piece or blank of felt, leather, or similar flexible material, which consists in forming the blank into bag-shape, then coating said bag-shaped blank with an adhesive, then permitting said adhesive to dry, then softening said bag-shaped blank by the application of steam thereto, and, finally, moulding the 30 bag-shaped blank between a die and a matrix.

35 In witness whereof, I have hereunto signed my name in the presence of two subscribing witnesses.

MARIO FRANCO.

Witnesses:

A. GULIO SACERDOTE,
ZMBERTO FRANCICONI.
